ROY N. FLACK AND LEWIS D. STURM, OF PORTLAND, OREGON.

DOOR OPENER.

Application filed October 28, 1924. Serial No. 746,311.

Our invention relates to door openers which are especially useful for garage doors, which however may be used to advantage in other places where it is desirable to open 5 and close doors from a distance. This invention consists of a reversible motor, distant starting switches, a cross head reciprocated by the motor, and cut-out switches actuated by the movement of the cross head.

10 The doors are connected with the cross head by means of links.

The objects of our invention are to provide a door opener which positively opens and closes doors from a distance; which is 15 easy to install, economical in operation, simple in manipulation, and fool-proof in construction.

Other objects and advantages are to be found in the construction and arrangement 20 of parts as will be described in the specification, and particularly pointed out in the appended claims.

We attain these objects with the mechanism illustrated in the accompanying drawings, in which—

25 Fig. 1 is a plan view of the door opener attached from the ceiling.

Fig. 2 is a side view of Fig. 1.

30 Fig. 3 is a diagram of a garage, indicating the position of the door opener at the ceiling, the distant starting switches for the motor, and the manner in which the door opener is connected with the doors.

Similar numerals refer to similar parts 35 throughout the several views.

The base board 1 is to be attached to a ceiling or any other suitable overhead support, with the operating mechanism either up or down. At one end of the base board 40 is a box 2 containing standard cut-out switches, the exposed handles of which are shown at 3. A standard outlet 4 sends the connecting wires 5 to the reversible motor 6. A lead screw 7 extends from the axis of

45 the motor 6 to the other end of the base board 1 and is there supported in a bracket or hanger 8. A similar hanger 9 supports the other end of the lead screw 7 near the motor 6. Connection between lead screw 7 and motor 6 is effected by a sleeve 10. Firmly mounted between the hangers 8 and 50 9 are the two rods 11 which serve as guide ways for the cross head 12. Two of the arms 13, with which the cross head 12 is 55 slidably mounted on the rods 11, are sufficiently far extended toward either side to

receive the holes 14 for the links to be enumerated later. A tongue 15 is integrally attached to the cross head 12 and projects to the same height as the hangers 8 and 9 and 60 parallel thereto. The lead screw 7 is screwably mounted in the tongue 15 and propels the cross head 12 back and forth. Slidably traversing the extreme ends of the tongue 15 and hangers 8 and 9 is a trip rod 16 which 65 extends past the motor 6 and engages pivotally the handles 3 of the cut-out switches in the box 2. On the trip rod 16 are the two collars 17 which partly limit the movement of the trip rod 16 and partly serve as 70 counter bearings for the helical compression springs 18. The latter have three distinct and important functions; one is to absorb the initial thrust of the approaching cross head 12 until the compression in the spring 75 becomes equal to or greater than the resistance offered by the trip rod 16, whereupon the latter, and therewith the cut-out switches, will be snapped quickly from one position into another—an essential requirement in switch operation; the other is to stop the momentum of the motor 6 after the current has been cut off, which results quite naturally through the resistance encountered by the cross head 12 when the spring 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850

The operation of the door opener can best be explained by means of the diagram in Fig. 3. The walls of the garage are indicated by the numerals 20, the doors by 21,

and the connecting links from the arms 13 to the doors by 22. This diagram also shows the relative position of the door opener on the ceiling of the garage. Three wires 23 lead from the cut-out switches in the box 2 to a reversible starting switch 24, which latter should be secured in front of the garage in a place easily accessible to an automobile driver from his seat. Three more wires 25 lead from the box 2 to a similar reversible starting switch 26 either within the garage or even in the home of the driver, if that should appear desirable. As the driver approaches the garage, he first operates the switch 24 which opens the doors 21 to the position indicated by the dotted lines. In leaving the garage by a rear exit, the manipulation of the switch 26 closes the doors. In leaving the garage by automobile, the driver may also close the doors with the switch 24. The numeral 27 indicates any suitable source of electric current.

The starting switches 24 and 26 may, of course, be provided with safety locks, if desired.

Having thus described our invention, it will be seen that our objects have been accomplished, and, though we have shown the preferred form of construction, we reserve to ourselves the right to make minor changes, provided we do not violate the spirit and principle of our invention.

We claim:

1. A door opener comprising a base board, cut-out switches mounted at one end of the base board, two hangers disposed in spaced relation at the other end of the base board, a lead screw rotatably mounted in the hangers, a motor between the end of the lead screw and the cut-out switches, said motor being firmly connected with the lead screw, guide rods rigidly mounted between the hangers parallel to the lead screw, a cross head slidably mounted on the guide rods, arms extending from the cross head laterally of the lead screw, said cross head being reciprocated by the lead screw, a tongue projecting from the cross head to the same height as the hangers, a trip rod operatively associated with the cross head and slidably traversing the extreme ends of the tongue and hangers, said trip rod extending past

the motor and connecting with the cut-out switches.

2. A door opener comprising a base board, cut-out switches mounted at one end of the base board, two hangers disposed in spaced relation at the other end of the base board and at the longitudinal center line thereof, a lead screw between the hangers and rotatably mounted therein, a motor attached to the lead screw adjacent to the cut-out switches, a cross head reciprocated by the lead screw, a tongue projecting from the cross head to the height of the extreme ends of the hangers, a trip rod slidably traversing the extreme ends of the tongue and hangers, collars affixed to the trip rod between the two hangers to limit the movement of said trip rod, and helical compression springs on the trip rod between the collars and tongue, said trip rod extending past the motor and connecting with the cut-out switches.

3. A door opener comprising a base board, cut-out switches mounted at one end of the base board, hangers at the longitudinal center line of the base board, a lead screw mounted between the hangers, a reversible motor connected to the end of the lead screw adjacent to the cut-out switches, said lead screw having a portion of the threads at both ends near the hangers removed, a cross head reciprocated by the lead screw and capable of entering that portion of the lead screw which has been diminished in diameter, a tongue projecting from the cross head to the same height as the hangers, a trip rod slidably traversing the extreme ends of the tongue and hangers, said trip rod extending past the motor and connecting with the cut-out switches, collars on the trip rod between the two hangers and helical compression springs mounted on the trip rod on each side of the tongue between collar and tongue and capable of re-engaging the cross head with the lead screw when said cross head enters that portion of the lead screw which has a diminished diameter and when the rotation of the motor is reversed.

Signed by us at Portland, Oregon this 17th day of October, 1924.

ROY N. FLACK.

L. D. STURM.
